UNITED STATES PATENT OFFICE

WALTER E. BLACK, OF CLEVELAND, OHIO, ASSIGNOR OF ONE-TENTH TO ARTHUR J. GILBERT, OF BROOKLYN, NEW YORK

ADVERTISING DISPLAY SIGN

Application filed May 7, 1930. Serial No. 450,355.

This invention relates, generally, to advertising display signs, and the invention has reference, more particularly, to a novel illuminated advertising display sign.

Display signs as heretofore generally constructed are largely utilitarian and more or less unattractive in design and though conveying the desired advertising information, nevertheless owing to the failure of such signs to appeal to the aesthetic sense, they are often completely ignored or avoided by the eye of the observer, resulting in the failure of the sign to convey the desired information.

The principal object of the present invention is to provide a novel illuminated advertising display sign which combines beauty of appearance with great utility in displaying advertising, whereby the attractiveness of the display catches the eye and causes the observer to read and remember the advertising information desired.

Another object of the present invention lies in the provision of an advertising display sign so constructed and arranged as to provide illuminating means for illuminating the advertising matter displayed on said sign and also providing for the illumination of the area upwardly and rearwardly of said sign, thereby adapting the same for use in show cases, display windows or other desired locations for displaying or illuminating either the merchandise advertised or other merchandise positioned above and rearwardly of the display sign.

Another object of the present invention is to provide a novel advertising display sign having suitable reflecting surfaces for diffusing and directing light rays upwardly and rearwardly of the same.

Still another object of the present invention lies in the provision of a simple, efficient and inexpensive advertising display sign which is readily portable and is equally suitable for use in many locations.

Other objects of the present invention, not at this time more particularly enumerated, will be clearly understood from the following detailed description of the same.

The invention is clearly illustrated in the accompanying drawings, in which:—

Fig. 1 is a view in front elevation of the novel advertising display sign of this invention;

Fig. 2 is a view in side elevation of the structure shown in Fig. 1;

Fig. 3 is a plan view of the structure shown in Fig. 1; and

Fig. 4 is an enlarged vertical sectional view of the novel advertising display sign, taken along line 4—4 of Fig. 3.

Similar characters of reference are employed in the above described views, to indicate corresponding parts.

Referring now to said drawings, the reference numeral 1 designates the novel advertising display sign of this invention as a whole. Display sign 1 comprises a base 2 preferably of cast metal, such as cast iron, and is of substantially rectangular shape in plan. Base 2 is illustrated as of hollow construction, being open at its bottom and closed at its top, said base having angular legs 3 at the corners thereof and stepped side walls 4 positioned above said legs. The top 5 of base 2 is provided with a central aperture 75 into which a hollow post 6 is threaded. Post 6 carries an electric light socket 7 into which a suitable electric light bulb 8 is adapted to be threaded.

A flexible electric supply cable or cord 9 connects with socket 7 and extends downwardly through post 6 and has its free end connected to a plug 10 for insertion into a suitable convenience outlet. The upper surface 12 of base top 5 is mirrored as by nickel or chromium plating the same, whereby this surface is rendered highly reflecting so that light rays falling thereupon from bulb 8 are reflected upwardly. The upper forward edge portion of top 5 is formed with a chamfer or recess 13 for receiving the lower edge portion of a translucent or opalescent glass or plate 14. Plate 14 is of substantially trapezoidal shape, having parallel upper and lower edges and upwardly and outwardly directed side edges.

Plate 14 is adapted to have any desired advertising or other matter 15 printed, painted or otherwise mounted thereon, the advertising matter shown in the drawing be-

ing merely an example for purposes of illustration. The plate 14, being translucent, does not enable the light bulb 8 to be seen directly therethrough, but nevertheless permits a desired portion of the light from bulb 8 to diffuse through this plate, thereby causing the advertising matter 15 to stand out strongly, as viewed from the front and enabling the easy reading of the same. The 10 lower edge portion of plate 14 is retained in fixed position within chamfer 13 by a plaque or U-shaped ornamental plate 16. The lower connecting portion 18 of plaque 16 is secured, as by screws 17, to the uppermost rise of the 15 stepped front wall 4 of base 2. The side legs of the U-shaped plaque 16 extend upwardly and outwardly at the ends of the connecting portion 18 and are positioned in overlying relation to the side edge portion of translucent plate 14. These side legs are embellished or 20 adorned with three successively arranged designs of substantially trapezoidal shape, simulating the shape of the translucent plate 14, thereby causing the display sign to have an 25 extremely attractive appearance as viewed from the front thereof.

The advertising display sign is provided at its sides and back with a reflecting shield 19, preferably of sheet metal and of a material which takes on and retains a high polish when buffed, such as aluminum. The interior surfaces of the walls of shield 19 are buffed, so that light falling upon them from bulb 8 is readily reflected. Reflecting shield 30 19 has its lower portion secured, as by screws 20, to the base 2 along the sides and the rear of this base. From the base 2, the reflecting shield 19 extends upwardly and outwardly as especially shown in Fig. 3, thereby providing outwardly inclined or flared inner side reflecting surfaces 21 and 22 and a back reflecting surface 23. The forward edges of the side walls of shield 19 are illustrated as 35 retained in abutting relation to the side edges of the translucent plate 14 by means of lugs 24 formed on the rear surface of plaque 16. The forward edges of the side walls of shield 19 are longer than the rear edges of these 40 walls, thereby causing the upper edges of the side walls to be downwardly and rearwardly inclined. This construction of the side walls prevents direct rays of light from the bulb 8 from striking the eyes of the observer, such 45 light as falls upon the side wall reflecting surfaces 21 and 22 being reflected upwardly and outwardly from the interior of the display sign.

In Fig. 4 there is illustrated by arrows the directions taken by a representative group 50 of rays passing from bulb 8. It will be noted that these rays are reflected from the surfaces 12, 21, 22 and 23 and from the rear wall of translucent plate 14 so that the rays from the light bulb 8 produce a flood of light extending upwardly and rearwardly and to

the sides from the advertising display sign, thereby effectively illuminating the area behind the display sign and enabling the same to be used for illuminating the goods advertised by the sign or other merchandise positioned behind the sign, while at the same time ample illumination of the advertising matter 15 is obtained.

It will be noted that the novel advertising display sign of the present invention is highly attractive as viewed from the front thereof, and is designed so as to prevent direct rays of light from bulb 8 from striking the eye of the observer, while at the same time the entire light output of the bulb 8 is utilized either to illuminate advertising matter 15 or to illuminate groups of other objects positioned behind, above and to the side of the advertising display sign.

Owing to the ready portability of the sign of this invention, the same may be used in or upon counters, in show windows or in other places wherever advertising and displaying is desired.

It will be apparent in some instances, as when a large volume of light is desired directly behind the novel advertising sign of this invention, that the portion of the reflecting shield 19 along the rear of the base 2, i. e. the reflecting surface 23 may be omitted, and at times the entire reflecting shield may be omitted. It will be obvious that the plate 14 may be mounted in various ways upon the forward part of the base 2 other than the manner shown. For example, this plate may be mounted in a channel member attached to base as will be apparent.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:—

1. An advertising display sign comprising in combination, a base, a translucent plate mounted upon the forward portion of said base and extending upwardly therefrom for receiving advertising matter to be illuminated, said plate having upwardly and outwardly inclined side edges, a source of light mounted upon said base rearwardly of said translucent plate for illuminating the advertising matter thereon, and a reflecting shield mounted upon said base in surrounding relation to said source of light, said reflecting shield having upwardly and outwardly inclined side and back walls, the top surface of said base and the inner surfaces of said reflecting shield being mirrored and cooperating with the rear surface of said translucent plate for reflecting and diffusing

light from said source upwardly and rearwardly with respect to said display sign.

2. An advertising display sign comprising in combination, a substantially rectangular base, a translucent plate of substantially trapezoidal shape having its lower edge portion mounted on said base and extending upwardly therefrom, advertising matter contained upon the forward surface of said translucent plate, a U-shaped plaque secured to said base and positioned forwardly of said translucent plate, a reflecting shield attached at its lower edge portion to the side and back walls of said base, said reflecting shield extending upwardly and outwardly from said base, and a light source mounted on the top of said base rearwardly of said translucent plate and within the confines of said reflecting shield, a portion of the light from said source passing through said translucent plate to define said advertising matter, and another portion of the light from said source being reflected from the rear surface of said translucent plate and from said reflecting shield so as to diffuse upwardly and rearwardly of said display sign.

3. An advertising display sign comprising in combination, a substantially rectangular base having a recess in the forward portion thereof, a translucent plate of substantially trapezoidal shape having its lower edge portion mounted in said recess and extending upwardly from said base, advertising matter contained on the forward surface of said translucent plate, a U-shaped plaque secured to said base and positioned forwardly of said translucent plate for retaining said plate in position in said recess, a reflecting shield attached at its lower edge portion to the side and back walls of said base, said reflecting shield extending upwardly and outwardly from said base and having interior reflecting surfaces, and a light source mounted on the top of said base rearwardly of said translucent plate and within the confines of said reflecting shield, a portion of the light from said source passing through said translucent plate to define said advertising matter and another portion of the light from said source being reflected from the rear surface of said translucent plate and from said reflecting shield so as to diffuse upwardly and rearwardly of said display sign.

4. An advertising display sign comprising in combination, a substantially rectangular base having stepped side walls and a top provided with a mirrored upper surface, said base having a recess in the forward portion thereof, a translucent plate of substantially trapezoidal shape having its lower edge portion mounted in said recess, advertising matter contained on the forward surface of said translucent plate, a U-shaped ornamental plaque secured to said base and positioned

forwardly of said translucent plate for retaining the latter in position in said recess, a reflecting shield having interior reflecting surfaces and being attached at its lower edge portion to the side and back walls of said base, said reflecting shield extending upwardly and outwardly from said base, and a light source mounted on the top of said base rearwardly of said translucent plate and within the confines of said reflecting shield, a portion of the light from said source passing through said translucent plate to define said advertising matter, and another portion of the light from said source being reflected from the rear surface of said translucent plate and from said reflecting shield so as to diffuse upwardly and rearwardly of said display sign, said mirrored base top aiding in the reflecting of the light.

In testimony, that I claim the invention set forth above I have hereunto set my hand this 21st day of April, 1930.

WALTER H. BLACK.
